No. 882,908.

PATENTED MAR. 24, 1908.

H. M. PIERSON.

METHOD OF MANUFACTURING GAS.

APPLICATION FILED APR. 22, 1907.

UNITED STATES PATENT OFFICE.

HENRY M. PIERSON, OF NEW YORK, N. Y.

METHOD OF MANUFACTURING GAS.

No. 882,908.

Specification of Letters Patent. Patented March 24, 1908.

Application filed April 22, 1907. Serial No. 369,467.

To all whom it may concern:

Be it known that I, HENRY M. PIERSON, a citizen of the United States, residing at the borough of Brooklyn, in the county of Kings, city and State of New York, have invented an Improvement in the Method of Manufacturing Gas, of which the following is a specification.

My invention relates to a method of manufacturing non-luminous water gas and fuel or producer gas, by which the economical and rapid production of these gases is made possible and by which at the same time a fuel is produced that is available in their manufacture.

My improved method consists generically in forcing air into and heating a body of fuel and making therein producer gas, passing the heated producer gas through a body of bituminous coal and thereby extracting the chemical substances therefrom, enriching the gas, and distilling the bituminous coal and so producing of the bituminous coal a fuel coke, conveying away the gases so formed and enriched and progressively delivering the coke onto the said body of fuel to replenish the same and progressively adding new bodies of bituminous coal to be progressively acted upon for the production of the said gases and the coke.

In the further carrying out of my improved method, the fuel or producer gas is made in the blowing up of the body of fuel in a suitable generator and the passing of the producer gas through the body of bituminous coal enriches the gas, heating up and distilling the bituminous coal; air under pressure being employed and forced into the said body of fuel, but no air is introduced into the apparatus to commingle with the producer gas.

Where it is desired to make only fuel or producer gas, a small quantity of steam may be advantageously introduced with the air beneath the generator grate-bars in the manufacture of the fuel or producer gas which passes away from the generator in its hot condition for any desired and immediate use in the arts where it is employed in connection with furnaces for treating or melting metal, but where the producer and water gases are made successively the steam must not be used with the air as it will lower the temperature of the fuel too much.

The production of the water or non-luminous gas is a substantial continuation of

the method of forming the producer or fuel gas, as after the generator has been blown up to incandescence the air is shut off and steam is introduced which passing through the body of incandescent fuel lowers the temperature thereof; the steam being resolved into its component parts and taking up from the body of fuel and the bituminous coal the necessary elements for the production of water or non-luminous gas. This non-luminous gas is conveyed away from the generator and is caused to pass through well known apparatus in this art, such as a washer and a scrubber so as to prepare the same fully for its work, and from these devices it is conveyed to a holder where the gas is both cooled and allowed to become cold, because the water or non-luminous gas is better in a cold state and in such state is used for gas engines.

In the drawing I have illustrated by a vertical section an apparatus capable of carrying out the process herein described. In this drawing, *a* represents the shell of a generator of suitable dimensions, *a'* the lining thereof, *b* the grate-bars, *b'* an air inlet, *c* a steam inlet, and this generator is preferably provided with stoke-holes *d d'* having removable covers. In connection with this generator I employ a vertically positioned tapering retort in which *e e'* are the metal shell portions supported upon eye-beams *f* which in turn are supported upon beams *g* laid at right angles thereto. The retort is composed of several similar tapering chambers *h h' h''* advantageously made of refractory material with flanges 2 3 and 4 at their upper ends and said retort chambers are supported from the shell parts by rings 5 6 and 7 which come between the parts of the shell *e e'* and between the lower shell and the upper shell of the generator which parts are supported on the eye-beams *f*. Above these retort chambers I provide a hopper *i* preferably supported above from a beam 8 and the lower portion of the hopper is made as a drum *i'* containing a revoluble feeder *k* of blades. The upper member of the retort is provided with a pipe *l* having a branch *l'* the pipe *l* and branch *l'* being provided with a valve *m*.

In the operation of this device for the production of non-luminous water gas and producer gas, the generator above the grate-bars is filled with fuel or with fuel and coke up to the mouth at the lower end of the re-

tort. The retort is filled with bituminous coal introduced by means of the hopper *i* and the revoluble feeder *k*; the drawing showing the position of the fuel and the height of the body of bituminous coal. The fuel in the generator is lighted and air under pressure is introduced through the air-inlet *b'*, the air being forced into the bed of fuel and causing imperfect combustion of the same. It is well known in this art that at a place in the depth of the fuel above the grate-bars the products of combustion are converted into producer gas which ascends through the remaining portion of the fuel before escaping. The producer gas from this body of fuel passes directly—and unmixed with air—up through the coke in the retort thereby heating and distilling the same and extracting the chemical substances therefrom. The producer gas thus formed passes off in a hot state through the pipe or throat *l'* and past the valve *m* which has been raised to the place at which the same is burned for heating furnaces for treating or melting metal, or other uses in the arts. During the process of making this producer gas, a little steam is advantageously introduced by the pipe *c* below the grate-bars, that is, a small quantity. This is not so much a necessity for making the producer gas as to keep down the temperature and prolong the operation of making the producer gas. After the fuel has been brought to the right point of heat and incandescence, and in the prolongation of the process for the formation of non-luminous watergas, the air is entirely shut off and steam is introduced under pressure, passing through the body of fuel, being decomposed thereby and passing up through the coke in the lower portion of the retort and the bituminous coal in the upper part of the retort forming non-luminous water gas, the valve *m* meanwhile having been closed to the producer gas outlet. The water or non-luminous gas then passes by the branch pipe or throat *l* and is preferably treated and its temperature reduced by passing through a washer and scrubber into a holder or gasometer where it is stored for future use to be mixed with air in suitable proportions as an explosive mixture for driving engines or other machines.

It is well known in this art that bituminous coal when partially coked and expanded by heat becomes packed and caked and is difficult to break up. I provide for this condition by employing a retort chamber much larger at the lower than at the upper end and in which the coal progressively moves down by gravity and the working of said expansive force, the very action of which is to break up and turn even the particles as they descend.

While I have shown in the drawing, an apparatus suitable for carrying out this method, I prefer to employ this apparatus in pairs so

that the supply of producer or fuel gas may be continuous and also the supply of water or non-luminous gas continuous, because while the one generator is making producer gas the other which has made the producer gas is at the same time making water or non-luminous gas, and vice versa; it being a fact that upon the completion of making the water or non-luminous gas the fuel in the generator is raked down and the coke in the retort allowed to be discharged therefrom into the generator as fuel for the further operations of the generator and a fresh charge of bituminous coal is introduced into the top of the retort from the hopper *i* through the revoluble feeder *k*.

While I have hereinbefore described a single apparatus with reference to the alternate production of producer and water or non-luminous gas, I prefer for the economical production of these gases continuously, to provide a duplication of the apparatus illustrated, so that the same may be coupled up in their gas pipes and run alternately for the continuous production of the respective gases, the one of which is a continuation of the method of producing the other.

In the method hereinbefore described by me, and because the generator and the retort opening therefrom and forming a continuation thereof produce an elongated fire chamber of hot fuel the steam undecomposed in the fire and heat of the generator is fully decomposed in the upper chambered end of the generator and in the heat of the retort, and considerable carbonic acid C_O_2 which in the manufacture of gas does escape in a shallow fire, is in my apparatus and process reconverted into C_O by the extra element of oxygen of the C_O_2 taking up an element of carbon in the retort and forming an additional volume of C_O , thus doubling the volume of this gas made and greatly increasing the heat units of the same.

I claim as my invention:

1. The method herein described of manufacturing gas, the same consisting in forcing air into and heating a body of fuel and making therein producer gas, passing the producer gas on and directly through a body of bituminous coal superimposed upon the body of fuel and forming an uninterrupted continuation thereof and thereby extracting the chemical substances therefrom and distilling the bituminous coal and conveying the hot gases so produced away for immediate use in the arts.

2. The method herein described of manufacturing gas, the same consisting in forcing air into and heating a body of fuel and making therein producer gas, passing the producer gas on and directly through a body of bituminous coal superimposed upon the body of fuel and thereby extracting the chemical substances therefrom and distilling the bitu-

minous coal and conveying the hot gases so produced away for immediate use in the arts, closing off the supply of air beneath the bed of fuel and the discharge of the gas and opening up the gas discharge in a different direction and then forcing steam through the bed of incandescent fuel and body of coke and bituminous coal and resolving the same into its component parts for the production of water or non-luminous gas and conveying the same away and storing it for future use.

3. The method herein described of manufacturing gas, the same consisting in forcing air into and heating a body of fuel and making therein producer gas, passing the producer gas on and directly through a body of bituminous coal superimposed upon the body of fuel and thereby extracting the chemical substances therefrom and distilling the bituminous coal and conveying the hot gases so produced away for immediate use in the arts, closing off the supply of air beneath the bed of fuel and the discharge of the gas and opening up the gas discharge in a different direction and then forcing steam through the bed of incandescent fuel and body of bituminous coal and resolving the same into its component parts for the production of water or non-luminous gas and conveying the same away and storing it for future use and so producing a fuel coke from the bituminous coal, progressively delivering the coke so formed onto the body of the fuel to replenish the same and progressively repeating the operations of the manufacture of gas.

4. The method herein described of manufacturing gas, the same consisting in forcing air into and heating a body of fuel and making therein producer gas, passing the producer gas on and directly through a body of

bituminous coal superimposed upon the body of fuel and thereby extracting the chemical substances therefrom and distilling the bituminous coal and conveying the hot gases so produced away for immediate use in the arts, progressively delivering the distilled bituminous coal as coke upon the body of fuel to replenish the same as the ashes of the body of fuel are removed and progressively replenishing the body of bituminous coal.

5. The method herein described of manufacturing gas, the same consisting in forcing air into and heating a body of fuel and making therein producer gas, passing the producer gas on and directly through and heating a body of bituminous coal superimposed upon the body of fuel and thereby extracting the chemical substances from and distilling the bituminous coal and conveying the hot gases so produced away for immediate use in the arts, closing off the supply of air beneath the bed of fuel and the discharge of the gas and opening up a gas discharge in a different direction, then forcing steam through the bed of heated bituminous coal and fully decomposing the same, re-converting the carbonic acid $C.O_2$ into carbonic oxid $C.O.$ by the extra element of oxygen of the $C.O_2$ combining with or taking up an element of carbon in the heated body of bituminous coal, all for the production of water or non-luminous gas and conveying the same away and storing it for future use.

Signed by me this 5th day of April 1907.
